GAME BOARD

Hartman Carr and John B. Fornberg,
Minneapolis, Minn.

Application April 13, 1949, Serial No. 1,942

Term of patent 7 years

(Cl. D34—5)

To all whom it may concern:

Be it known that we, Hartman Carr and John B. Fornberg, citizens of the United States, residing at Minneapolis, in the county of Hennepin and State of Minnesota, have invented a new, original, and ornamental Design for a Game-Board, of which the following is a specification, reference being had to the accompanying drawing, forming part thereof.

Referring to the drawing, the figure is a view in perspective of a game-board, showing our new design.

We claim:

The ornamental design for a game-board, as shown.

HARTMAN CARR.
JOHN B. FORNBERG.
